(57) **CLAIM**

The ornamental design for a travel pillow, as shown and described.

DESCRIPTION

FIG. 1 is a perspective view of an embodiment of a travel pillow with an inner pocket partially showing;

FIG. 2 is a perspective view of the travel pillow embodiment of FIG. 1 with the inner pocket extended;

FIG. 3 is an opposite perspective view of the travel pillow embodiment of FIG. 1; and,

FIG. 4 is a perspective view of another embodiment of the travel pillow showing an alternate zipper.

The broken lines in the drawings are included for the purpose of showing an exemplary placement of a logo on the travel pillow and form no part of the claimed design.
